(57) **CLAIM**

The ornamental design for a power connector assembly for artificial tree lighting, as shown and described.

DESCRIPTION

FIG. 1 is a perspective view of the bottom piece of a power connector assembly for artificial tree lighting showing my new design;

FIG. 2 is a front view of FIG. 1 thereof;

FIG. 3 is a back view of FIG. 1 thereof;

FIG. 4 is a right side view of FIG. 1, the left side being a mirror image thereof;

FIG. 5 is a top view of FIG. 1 thereof, and

FIG. 6 is a bottom view of FIG. 1 thereof.

FIG. 7 is a perspective view of the top piece of a power connector assembly for artificial tree lighting showing my new design;

FIG. 8 is a front view of FIG. 7 thereof;

FIG. 9 is a back view of FIG. 7 thereof;

FIG. 10 is a right side view of FIG. 7, the left side being a mirror image thereof;

FIG. 11 is a top view of FIG. 7 thereof; and,

FIG. 12 is a bottom view of FIG. 7 thereof.

The broken line portions in the figures illustrate the portions of the design that form no part of the claimed design.

1 Claim, 8 Drawing Sheets(56)
